SLEEVE SET

Application filed May 18, 1923. Serial No. 278,777.

My invention relates to the tailoring art, being more particularly a device by means of which a sleeve may be marked or "notched", enabling the operator to properly place the sleeve in the sleeve hole of a garment for the purpose of basting the same in place.

Ordinarily, in tailoring, the sleeve opening in the body of a garment, such as a coat, 10 and the open end of the sleeve are irregular in shape and of unequal size, under which conditions it is, in common practice, more or less a matter of guess work in placing the sleeve in the sleeve opening.

15 It also frequently happens that the sleeves as made up separately have either a much larger top opening in the coat or, in some cases, a considerably smaller opening. An additional difficulty in properly placing the 20 sleeve in the coat for basting is the placing of the sleeve so that the sleeve will hang properly when finally sewed in place.

Due to the objections noted above, the operation of basting sleeves in the coat takes 25 considerable time and in many instances the operation is performed several times before the sleeve is properly placed in the coat.

The principal object of my invention is to 30 produce a sleeve set of simple form and construction, by means of which a sleeve may be marked or notched to correspond to marks or notches placed on the sleeve opening in the coat, such corresponding marks insuring the proper placing of the sleeve in the coat and 35 the consequent proper hang of the sleeve when finished.

40 Due to the fact that tailors have no convenient means for readily determining the circumference of the arm hole in a sleeve after it is "made up", nor are any means available for shaping a "made up" sleeve to conform to a specified circumference, the sleeve set is provided with graduations by means of which the circumference may be 45 readily determined merely by placing the set upon the flattened sleeve in a manner as will be hereinafter described.

These graduations may also be used in 50 shaping the sleeve to conform to any specified circumference.

It will be understood that the opening in the sleeve need not necessarily have the same circumference as the arm hole in the garment, since the cloth in either the sleeve or the body of the garment may be easily stretched or 55 taken in to give certain fullness or style effect, as will be understood by those familiar with the art.

Other objects and advantages of my invention will appear hereinafter from the following description and the appended claims.

Referring to the drawings, which are for illustrative purposes only,

Fig. 1 is a face view of a sleeve set embodying the preferred form of my invention. 65

Fig. 2 is a diagrammatic view of the first operation of "notching" of the sleeve hole of a coat.

Fig. 3 is a diagrammatic view of the shoulder portion of the coat, showing the second 70 operation of "notching" the sleeve hole.

Fig. 4 is a diagrammatic view of the shoulder portion of the coat, showing the manner of using the set to measure such sleeve opening. 75

Figs. 5, 6 and 7 are diagrammatic views of 80 a sleeve illustrating different operations of using the sleeve set to place notches thereon corresponding to the notches on the sleeve hole of the coat.

Fig. 8 is a diagrammatic view showing the sleeve in the position which it will normally occupy when being worn.

More specifically describing the embodiment of my invention, as illustrated in the 85 drawings, the sleeve set generally indicated at 15 consists of a flat stick or handle portion 16 and a transverse stick 17 which, together with the handle, forms in general outline a cross.

A straight line, such as indicated by the dotted line 18, runs through the intersection point designated at 19 of the upper or measuring edge 20 of the cross stick 17 and the measuring edge 21 of the main stick 16 and 90 through the forward or front corner 22 at the lower edge of the main stick 16.

It will be noted that the measuring edge 21 of the main stick 16 is angularly disposed with respect to the straight line 18, being 100

arranged at approximately 10° from the vertical and consequently being angularly disposed with respect to the measuring edge 20 of the cross stick, the purpose of such angularity of the measuring edge 21 being to accommodate the offset from the vertical of a sleeve when properly placed in the sleeve opening of the coat.

Arranged on the upper end of the main stick 16 above the central point 19 is a top notch scale 24, a corresponding scale 25 for the bottom notch being arranged on the main stick below the pivot or central point 19.

It is to be noted that the lowest mark of the scale 24 is substantially half again as far above the intersection point 19 as the corresponding highest mark on the bottom scale 25, such arrangement being for the purpose of allowing for the rounding of the sleeve over the shoulder on the upper part of the sleeve, bearing in mind that when the set is used, the sleeve is lying flat, consequently an allowance must be made above the intersection point 19 for the extra material in the sleeve curving over the shoulder to the shoulder seam of the coat.

The cross or transverse bar is also provided with scales 27 and 28, the scale 27 being designated the front notch scale, and the scale 28 the rear notch scale. It will be noted from Fig. 1 that the graduations on all of the scales are numbered away from the point of intersection 19 of the two sticks. In other words, in the form illustrated, the first graduation of each scale is positioned intermediate the intersection point and the end of the scale, and is designated by number 12. The remaining numbers increase consecutively away from the point of intersection toward the ends of the scales.

For the purpose of better understanding the sleeve set, the method of using the same may be described as follows: The first operation performed is to mark the sleeve opening of the coat with a top notch. This may be done in several ways, but a simple manner of performing this operation is to place one hand (as shown in Fig. 2) under the central part of the coat at the back thereof, so that the coat is balanced in hanging on each side of the hand. Then by inserting the fingers of the other hand in the sleeve opening, the coat is again balanced at two points, that is, at the back of the collar and at the top of the sleeve opening.

When the coat is balanced, a mark by means of chalk or other suitable material, is placed on the coat at the sleeve opening where the same is resting on the fingers, as illustrated at 30 in Fig. 2, which point may be designated as the coat top notch 30.

As shown in Fig. 3, the coat is then placed on the table and flattened out, with the front of the coat uppermost, so that the top notch 30 on the coat forms the upper point, the

sleeve opening being open and the point of folding at the lower end of the sleeve opening being marked and constituting bottom notch 31.

With these marks inserted and placed on the coat as described, the operation of using the sleeve set may be followed out. As shown in Fig. 4, the coat is in the same position as shown in Fig. 3, the sleeve set 15 being laid across the sleeve opening on the coat and the set moved until corresponding number on the scales 27 and 28 coincide, the one on scale 27 with the bottom notch 31 of the coat, and the one on the scale 28 with the top notch 30 of the coat, but approximately three-quarters of an inch upwardly on the shoulder from such top notch, to allow, as indicated in dotted lines at 32, for seams.

In the illustrations used, I have selected the numerals 26 as the corresponding numerals on the scales 27 and 28, and when the set is placed on the coat, as shown in Fig. 4, a point corresponding to a so-called "front notch" is selected on the scale one-half to three quarters of an inch inside the opening on the dotted line 32, which, for the purpose of illustrating the numeral 18 on such scale, is selected. A "rear notch" is placed upon the back of the armhole opening in a similar manner. These numerals 26 and 18 are the basis for the "notching" of the sleeves, and the operation as indicated in Fig. 4 of the drawings may be considered the measuring operation.

With numerals 26 and 18 to work with, the numeral 26 being the length of the sleeve opening and the numeral 18 designating the width of the sleeve opening, the set is placed on the sleeve with the front edge of the lower end or guide portion of the main stick tangent to the front corner of the lower edge of the folded sleeve as shown in Fig. 6, the set being adjusted so that the mark 26 on scale 24 is at the upper edge of the sleeve, and the numeral 18 on the scale 27 being placed at the front edge of the sleeve, the graduations on the scale are so arranged that in a normal sleeve, having a circumference equal to that of the arm hole in the coat, the numerals 26 on scale 25 will fall on the lower front edge of the sleeve opening. If, however, the sleeve opening is smaller than the coat opening, as in the case illustrated, the numeral 26 on scale 25 will fall at a point slightly within the cut edge of the sleeve, as shown in Fig. 5. When the set is in such position, a front notch is placed on the sleeve as indicated at "a" and a rear notch and bottom notch are placed upon the sleeve as indicated at "b" and "c" respectively. These notches, as shown in Fig. 5, are placed upon the sleeve at points tangent to the respective scales 27, 28 and 25.

For the purpose of obtaining the top notch on the sleeve, a mark indicated at 34 is placed upon the sleeve in parallel relation to the

measuring edge 21 of the main stick 16. This mark extends from the upper right hand corner 35 of the sleeve downwardly to the horizontal scale 28.

- 5 The set is then swung in the direction of the arrow in Fig. 6, pivoting about the point 22' at the lower corner of the sleeve until the mark or graduation 18 on scale 28 is opposite the mark 34 as shown in Fig. 6. The top 10 "notch" "d" is placed upon the sleeve by making a mark tangent to scale 24 at the top of the sleeve while in the position shown in Fig. 6.

A shaping scale 36 may be placed upon the 15 cross on transverse member 17 of the set, directly below the scale 28. The graduations on this scale are offset toward the intersecting point 19 substantially three-quarters of an inch, and are slanted in the direction giving 20 the best results in basting a sleeve in place.

This scale is used when the set is in the position shown in Fig. 6, a mark "e" being placed upon the sleeve in the position of graduation 18 on scale 36. This mark, which is given the same slant as the graduations on scale 36, indicates the line along which the sleeve is to be basted.

The apparent unsymmetrical arrangement 30 of "notches" upon the sleeve, and in the case of "abnormal" sleeves (such as those having an arm hole opening of different circumference than the opening in the coat) the swinging movement of the scale, is necessary due 35 to the fact that the sleeve, when receiving such marks is lying flat, and when picked up the material, for instance such as indicated at "f" and "g" in Fig. 6 moves inwardly to assume the proper shape as shown in Fig. 8.

40 As was previously mentioned, this set was developed to provide a convenient means of rapidly determining the circumference in inches of the arm hole in the sleeve, merely by placing the set upon the sleeve in a manner 45 such that the graduations at which diametrically opposite scales fall upon the edge of the sleeve opening are the same. The circumference of the opening is the arithmetic mean of the readings upon the vertical and 50 horizontal scale. Take, for instance, the sleeve shown in Fig. 7, on which the longitudinal scale readings are 24 and 24 and the transverse scale readings are 20 and 20, the circumference of this sleeve will be

$$\frac{24+20}{2}$$

or 22 inches.

Although the shapes of sleeve openings have 60 no regular geometric form, they are more or less uniform and this means of determining the circumference, which has been developed largely through experimentation, has been found to give results of consistent accuracy 65 greater than the industry demands.

In the preferred embodiment of this invention whereby most satisfactory results are obtained, the longitudinal measuring member 21 is offset at substantially 10° from a straight line 18 passing through the transverse measuring edge 20 at right angles thereto. Corresponding divisions on the transverse edge 20 are spaced equidistant with graduation number "12" substantially two and one-eighths inches from the intersecting point 19 and the distance between the graduations is substantially five-sixteenths of an inch. The bottom graduation on the "top" scale 24 is one and seven-eighths inches above the intersection point 19, and the top graduation on scale 25 is substantially one and one-eighth inch below the point 19, and the distance between the graduations on these scales is substantially nine thirty-seconds of an inch.

It is to be understood that the circumference measuring feature of this sleeve set is restricted to a construction following more, or less specifically this form illustrated, but for the purpose of obtaining the aforementioned notches, the spacing and numbering of the graduations may be varied without affecting the operation, or the results obtained with the instrument.

I claim as my invention:

1. A sleeve set for garments comprising: a main stick; a cross stick attached to said main stick, said main stick and said cross stick having intersecting scale edges; there being identical graduations indicated on all of said scale edges on opposite sides of the point of intersection, the distance from one of the initial graduations on the main stick to the point of intersection being substantially one and one half times the distance from the other initial graduation on said main stick to said point of intersection.

2. A device for measuring the circumference of arm hole openings in sleeves when said sleeves are in a flattened position which embodies: a transverse member; a longitudinal member mounted upon said transverse member at an angle of substantially 80° with said transverse member, said members being provided with scale sections positioned on opposite sides of the point of intersection between said members.

3. A device for measuring the circumference of arm hole openings in sleeves when said sleeves are in flattened position which embodies: a longitudinal member; a transverse member fixedly mounted thereon at an angle of substantially 80° therewith, both of said members being provided with graduated scale sections formed on opposite sides of the point of intersection of said members, the respective scale sections on one of said members having their initial correspondingly numbered graduations equidistant from said point of intersection, and the initial gradu-

tions of the scale sections on the other of said members being unequally spaced from said point of intersection in the ratio of substantially one and one half to one.

In testimony whereof, I have hereunto set my hand at Los Angeles, California, this 11th day of May, 1928.

STANLEY E. TRAGLER.
